UNITED STATES PATENT OFFICE.

LEONARD B. CHADWICK, OF BOSTON, MASSACHUSETTS.

AUTOMATIC PENCIL-SHARPENER.

No. 894,600.

Specification of Letters Patent.

Patented July 28, 1908.

Application filed November 2, 1907. Serial No. 400,342.

To all whom it may concern:

Be it known that I, LEONARD B. CHADWICK, a citizen of the United States, and a resident of Chelsea, Boston, in the county of 5 Suffolk and State of Massachusetts, have invented a new and Improved Automatic Pencil-Sharpener, of which the following is a full, clear, and exact description.

The purpose of this invention is to provide 10 novel details of construction for a pencil sharpener, preferably operated by electricity, and which will produce a fine tapered point on the pencil, the act of placing a pencil in the machine starting the same and continuing the operation until the pencil is removed.

The invention consists in the novel construction and combination of parts, as is hereinafter described and defined in the 20 appended claims.

Reference is to be had to the accompanying drawings forming a part of this specification, in which similar characters of reference indicate corresponding parts in all the views.

25 Figure 1 is a plan view of the machine, showing parts adjusted by an insertion of a pencil for closing an electric circuit and starting the cutting mechanism that operates thereon; Fig. 2 is a side elevational view of 30 the improved pencil sharpener, having a pencil inserted therein; Fig. 3 is a vertical sectional side view of the machine, substantially on the line 3—3 in Fig. 1; Fig. 4 is a transverse sectional view of details of the 35 machine, substantially on the line 4—4 in Fig. 5; Fig. 5 is a plan view of the sharpener device, showing the relative positions of parts when not in operation, and Fig. 6 is a sectional plan view, substantially on the line 40 6—6 in Fig. 3.

In the drawings, 10 indicates an electric motor of any improved construction, the details of which it is not necessary to illustrate and describe further than the power transmitting means thereon which will herein- 45 after be further mentioned.

Upon a side wall of the motor casing a bracket frame 11 is secured, and integral therewith is a horizontal plate-like formation 50 11^a, having a preferably circular edge and a central depending hub *a*, the plate and hub having a central bore therein.

An internal gear 12 is secured upon the lower side of the bracket plate 11^a, concentric with the hub *a*, the teeth of said gear being 55 slightly beveled toward their lower ends

for a purpose that will be hereinafter explained.

A bevel gear 13, of considerable diameter and preferably having its teeth upon the upper side thereof, is formed or secured upon an elongated hollow spindle 13^a that depends centrally from the lower side of the gear and has a radial flange 13^b formed on its lower portion.

Upon the casing of the motor 10, an arm 14 is secured, which projects laterally and at the outer end thereof terminates in a step box 14^a that receives support from a post 14^b resting on the same base with the motor 10.

In the step box 14^a, is rotatably seated the reduced lower end or point *b* of the spindle 13^a, as indicated by dotted lines in Fig. 2, and a washer *b'* for reducing friction is placed between the spindle and step box 14^a. An 75 annular flange *c* is formed upon the upper side of the bevel gear 13, concentric with its rim, and upon said flange is rotatably seated the true counterboard lower end of a sleeve 15, that is cylindrical in its body and at the 80 upper end thereof is bedded and secured in an annular recess *a'*, formed in the lower end of the hub *a*, as is clearly shown in Fig. 3. The bore in the spindle 13^a is conical, converging downwardly, as shown in Fig. 3 at *d*, 85 said conical bore extending from the annular flange *c* to the radial flange 13^b, and as shown in Figs. 3 and 6, one side *d'* of said spindle is cut out from the lower end thereof to a point near the lower side of the bevel gear 13, thus 90 forming a lateral opening into the conical bore *d* of the spindle.

A guide tube 16 having two opposed resilient jaws *e*, at or near each end thereof, is fitted closely at its longitudinal center in the 95 sleeve 15, the upper pair of jaws extending a distance above the bracket plate 11^a, said jaws having their inner corners convexed to permit the free insertion of the blunt end of a lead pencil *A* downward through the same, 100 as indicated in Fig. 2.

Upon the gear wheel 13 is mounted a bow-shaped bracket and arm 17 and secured at its spaced ends, said arm inclining outward and having at the crown of its bent portion 105 a perforation therein. On the upper side of the radial flange 13^b, opposite the flat side of the spindle 13^a, an inclined face is formed, and in said inclined face a socket *f* is produced. A cylindrical cutter shaft 18 is 110 formed at one end with a journal or "point" *f'*, that is stepped into the socket formed to

receive it in the radial flange 13^b, as shown in Fig. 3. The shaft 18 is inclined outward, and passes loosely up through the bevel gear 13 and then through a perforation in the 5 crown of the bracket arm 17, that serves as a bearing box therefor, a collar *g* being mounted and adjustably secured on the shaft below said crown, and between the latter and the collar one or more anti-friction 10 washers *g'* are preferably introduced.

The shaft 18 extends a distance above the bracket arm 17, and upon the upper end thereof a spur pinion 18^a is mounted and secured, which meshes with the teeth of the 15 internal gear 12, that converge so as to permit free rotatable movement of the pinion. A cutter head 19, consisting of an elongated barrel having a central longitudinal bore and a plurality of spiral cutter blades *h*, is mounted 20 and removably secured upon the shaft 18 by means of set screws *i*, and as shown in Figs. 2 and 3, the cutter head rests upon anti-friction washers *f'* that are mounted upon the point *f* of the shaft 18 and contact 25 with the beveled upper surface of the radial flange 13^b and the lower end of said cutter head.

The diameter of the cutter head and relative position had by the shaft 18, locates the 30 cutting edges of said cutter head slightly within the coniform bore *d* of the spindle 13^a.

A bevel pinion 20, secured on a shaft, not shown, that projects from the motor 10, meshes with the bevel gear 13, as shown in 35 Fig. 2, and it will be obvious that a rotation of the pinion by the motor will correspondingly rotate the gear 13 and the spindle 13^a.

Upon the frame 11, a block *m*, formed of material that is a non-conductor of electricity, 40 is secured, as shown in Figs. 1 and 5, and upon said block one end of a current conducting wire *m'*, is secured by a screw *n*, the head of which forms a contact point, and preferably the wire *m'* is positive in sign.

45 On the bracket plate 11^a, at a suitable point, a switch arm *o* is pivoted between its ends, as indicated at *o'* in Figs. 1 and 5. Upon an end portion of the switch arm *o*, that is furthest from the center of the bracket 50 plate 11^a, one end of a negative conductor wire *p* is secured by a metal screw *p'*, that passes through the arm and through one end of a resilient finger plate *p*², thus securing the latter upon said arm. The finger plate *p*², 55 that is a conductor of electricity, is at its free end positioned near the contact point *n*, and is normally held away from it by a spring *r*, that at its ends respectively engages the switch arm *o* and bracket frame 11, as shown in Fig. 5, and thus breaks electric connection 60 between the finger plate *p*², that is virtually an extension of the wire *p*, and the contact *n* that is the terminal of the conductor wire *m'*.

A toe *o*² is formed at one side of and near 65 the end on the switch arm *o*, that is extended

toward the jaws *e* on the guide tube 16, and projects between them, the spring *r* serving to enforce such an adjustment of the toe, as shown in Figs. 4 and 5. The toe *o*² is sloped 70 on its upper side from the arm *o*, to the free end thereof, and normally projects between the clamping jaws *e*, so as to partly occupy the passage therebetween.

In operation, assuming that the motor 10 is in effective condition, the normally open 75 circuit between the terminals of its conducting wires, will be closed upon pressing the cylindrical wooden body of an ordinary lead pencil *A* down between the jaws *e* on the guide tube 16, as this will press on the toe *o*² and rock the switch arm *o* so as to impinge the contact finger *p*² upon the contact point *n*, and start the motor in operation so as to rotate the pinion 20. It will be seen that the 80 rotary motion of the pinion 20 will turn the gear 13 at a slow speed, and the shaft 18 will receive orbital motion, which will cause the pinion 18^a to traverse the circular path of the teeth of the internal gear 12 and thus be caused to rotate rapidly. The rotation of 85 the pinion 18^a and shaft 18 will correspondingly rotate the cutter head 19, in a proper direction for a shear cutting action on the wooden body of the pencil *A*, that by its insertion down in the guide tube 16, is held opposite the cutter head.

If the pencil has never been sharpened, its 90 insertion should be graduated so that the wood will be removed by the cutter blades in thin shavings, that will rapidly give a conically tapered form to the body, and correspondingly to the lead core of the pencil, this being due to the bodily rotation of the spindle and cutter head 19 around the stationary pencil, and the independent rapid rotary 95 movement of said cutter head.

When the pencil has been sharpened to 100 give it a fine point, it may be removed from the clamping jaws *e* by an upward pull, and when so removed the switch arm *o* will assume its normal adjustment due to the stress of the spring *r*, which will open the circuit 105 and stop the machine.

Having thus described my invention, I 110 claim as new and desire to secure by Letters Patent:

1. The combination with a stationary bracket frame, an internal gear carried by said frame, a guide tube central in the internal gear and depending therethrough, resilient clamping jaws on the guide tube, a hollow spindle having a conical bore, means for supporting the spindle loosely in engagement with the internal gear, said spindle having a lateral opening that intersects its 115 conical bore, means for rotating the spindle, and a projection on the lower portion of the spindle, of a cutter shaft stepped in said projection, a pinion on the upper end of the 120 shaft meshing with the internal gear, a cutter 125 having a lateral opening that intersects its conical bore, means for rotating the cutter, and a projection on the lower portion of the cutter shaft stepped in said projection, a pinion on the upper end of the 130 cutter shaft meshing with the internal gear, a cutter

blade having spiral blades that project slightly into the conical bore of the spindle, and means for rotatably supporting the shaft.

2. The combination with a stationary bracket frame, an internal gear carried by said frame, a hollow spindle loosely supported from the internal gear and having a conical bore, means for guiding a pencil into said conical bore, said spindle having a lateral opening that intersects its bore, a bevel gear on the spindle, a lateral projection on the lower portion of the spindle; and means for rotating said gear, of a cutter shaft rotatably supported at its lower end in said projection from the lower portion of the spindle, a pinion on the upper end of said shaft and meshed with the internal gear, and a cutter head having blades that project slightly into the bore of the spindle through the lateral opening therein.

3. The combination with a stationary bracket frame, an internal gear carried by said frame, a sleeve depending from said gear, a hollow spindle having a conical bore, said spindle having a lateral opening therein, a guide tube having resilient jaws and held in the sleeve, a bevel gear secured on the spindle, and means for rotating said gear, of a cutter shaft, a lateral projection on the lower portion of the spindle wherein the cutter shaft is stepped at its lower end, an arm on the bevel gear projected upward and outward, said arm having a perforation in its upper portion that receives the cutter shaft and af-

fords support thereto, a pinion secured on the upper end of the cutter shaft that meshes with the internal gear, and a cutter head securable on the shaft, and having a plurality of spiral blades that project slightly into the lateral opening in the hollow spindle.

4. The combination with an electric motor, and a laterally supported pinion rotated by the motor, of a pencil sharpener, comprising a bracket frame projected laterally from the motor, an internal gear fixed on said frame, a hollow spindle loosely connected with the internal gear, and supported for rotation thereon, said spindle having a conical bore and a lateral opening thereinto, a vertical guide tube fixed centrally in the internal gear, said guide tube having spaced clamping jaws adapted for clasping a pencil, a cutter device having geared connection with the internal gear, and positioned at the side of the opening in the spindle, a bevel gear fixed on the spindle and meshing with the pinion carried by the motor, the latter being normally in open circuit, which circuit is closed and the motor energized upon an insertion of a pencil down through the clasping jaws and into engagement with the cutting device.

In testimony whereof I have signed my name to this specification in the presence of two subscribing witnesses.
